CLAIM

The ornamental design for a motor sailor, as shown and described.

DESCRIPTION

FIG. 1 is a perspective view of the present invention;

FIG. 2 is a top view of the present invention;

FIG. 3 is a side view of the present invention, the opposite side being identical;

FIG. 4 is a front view of the present invention;

FIG. 5 is a rear view of the present invention; and,

FIG. 6 is a bottom view of the present invention.

The broken lines are for illustrative purposes only and form no part of the claimed design. Portions of FIGS. 3–5 have been shown broken away for ease and clarity of illustration.
